UNITED STATES PATENT OFFICE.

THOMAS JENNI, OF ALLEGHENY, PENNSYLVANIA.

STEAM-ENGINE.

SPECIFICATION forming part of Letters Patent No. 338,076, dated March 16, 1886.

Application filed July 30, 1885. Serial No. 173,088. (No model.)

To all whom it may concern:

Be it known that I, THOMAS JENNI, a citizen of the republic of Switzerland, residing at Allegheny, in the county of Allegheny and 5 State of Pennsylvania, have invented certain new and useful Improvements in Steam-Engines, of which the following is a specification, reference being had to the accompanying drawings.

10 My invention relates to an improvement in steam-engines; and it consists in the combination of the operating-shaft, which has one of its ends projecting directly through the side of the valve-chest, the rotary valve connected 15 to this shaft, a gear-wheel, which is applied directly to the shaft, and the governor, which projects down through the top of the steam-chest and is provided with a gear on its lower end to mesh with the wheel on the shaft, 20 whereby the governor and the valve are driven directly from the shaft, as will be more fully described hereinafter.

25 The advantages I claim for my valve are the simplicity and consequent facility of construction, its durability and aptness for increasing or diminishing the volume of steam by the number of openings through which the steam enters into the cylinder, and the closeness with which it revolves in its seat.

30 The accompanying drawings represent my invention.

Figure 1 is a side elevation and section through the steam-chest. Fig. 2, a sectional elevation of the cylinder and steam-chest. 35 Fig. 3, an inside view of the steam-chest, showing the valve-seat, the steam and exhaust ports. Fig. 4 is a perspective view of the valve with only one opening for steam and the steam-chamber. Fig. 5 is a view of 40 the same with an elongated opening.

A represents a valve-rod with a bevel wheel, B', at one end that meshes a similar wheel, B, on the main shaft. The other end of the rod A enters the steam-chest H, and, in 45 the form of a key terminates in the center of valve D. At the inside of the steam-chest, on the rod, is a bevel wheel, C, meshing with wheel C' that operates the governor G.

D, Fig. 2, is a disk forming a circular ro-

tating valve with one or more openings, 5, according to the volume of steam desired to enter the cylinder, having a chamber, 4, that conducts the steam to the exhaust 3.

E represents the cylinder, and F a vertical rod, raised or depressed by the governor to 55 close or open a valve in the box I to shut off or admit steam.

The operation is as follows: Steam being admitted into the steam-chest H, enters the port 1 through the opening or openings 5 in 60 the valve D, and passes into the cylinder E behind the piston to set the engine in motion. The valve D, turning with the revolving shaft or rod A, allows the steam, after propelling the piston, to pass into port 2, whence it 65 enters the chamber 4 to escape through the exhaust-port 3. Thus the valve-rod A, connected by bevel gearing with the main shaft, turns the valve D and presents the openings 5 successively to the steam-ports 1 and 2, to 70 receive and exhaust the steam alternately.

As hereinbefore stated, the opening 5 in the valve may be a single one, as shown in Fig. 4, when only a small volume of steam is required, or the number may be increased to 75 two, three, or more, according to the power needed. The bevel wheels C C' connect the valve-rod A with the governor G, to which the cross-bar J is attached, that when the speed of the governor is increased, raises the rod 80 F to diminish or cut off steam by closing a valve in the box I.

Having thus described my invention, I claim—

The combination of the driving-shaft of the 85 engine, the wheel B, applied thereto, the shaft A, having the wheel B' secured to one end and having its other end to project through the side of the steam-chest, with the wheel C for operating the governor, and the rotary 90 valve, which is applied directly to the end of the shaft, substantially as set forth.

In testimony whereof I affix my signature in presence of two witnesses.

THOMAS JENNI.
